INVENTOR
Bernard T. Leveque

UNITED STATES PATENT OFFICE.

BERNARD T. LEVEQUE, OF WENHAM, MASSACHUSETTS, ASSIGNOR, BY MESNE ASSIGNMENTS, TO UNITED SHOE MACHINE CORPORATION, OF PATERSON, NEW JERSEY, A CORPORATION OF NEW JERSEY.

TOE-BINDING MACHINE.

Application filed January 31, 1917, Serial No. 145,775. Renewed February 28, 1922. Serial No. 539,910.

To all whom it may concern:

Be it known that I, BERNARD T. LEVEQUE, a citizen of the United States, residing at Wenham, in the county of Essex and State of Massachusetts, have invented certain improvements in Toe-Binding Machines, of which the following description, in connection with the accompanying drawings, is a specification, like reference characters on the drawings indicating like parts in the several figures.

This invention relates to mechanism adapted for use in binding the toe portions of shoe uppers in fastened position and herein the invention is shown operatively embodied in a lasting machine of that type in which the upper is worked over a last step-by-step in the operation of the machine on different portions of the upper materials successively, although it will be recognized that in various novel aspects the invention is not limited to machines of the type illustrated.

The toe binding mechanism in which I have chosen to embody this invention for illustrative purposes is herein shown as applied to a lasting machine of the hand method type similar to that shown in United States Letters Patent No. 581,714, granted June 15, 1897, on application of Ladd & McElroy, said machine being equipped for heel and toe shoe lasting with the improvements disclosed in United States Letters Patent No. 696,740, granted April 1, 1902, on application of A. W. Ladd, to which reference may be had for a more complete description of the construction and operation of the several lasting instrumentalities of the machine than it is necessary to present in connection with the present invention.

The toe binding material most generally used is soft iron wire which heretofore in the use of the hand method type of machine has been manually anchored at the side of the toe portion of the shoe where the toe lasting is to begin, by coiling the end of it about a tack already driven into the shoe in a previous operation, or about a tack especially driven for the purpose. As the lasting operation of the machine progresses, the wire is drawn around the toe to the other side of the shoe where it is manually

coiled about another similar tack and severed.

An object of this invention is to facilitate the application of binding material to the toes of shoes.

To this and other ends a feature of the invention consists in novel binder fastening means, the construction shown comprising means for fastening a toe binder at the opposite sides of a shoe successively by securing one end of the binder to the toe before the toe lasting operation is begun and by securing the opposite end of the binder to the shoe on the other side of the toe after the lasting operation is finished.

A further feature of the invention consists in a novel combination of binder forming means constructed and arranged to condition the binder for attachment to a shoe toe and means for operating upon the binder to secure it to the shoe. In the machine shown each end portion of the binder is first shaped to condition it for attachment to the shoe and is subsequently fastened to the shoe.

The invention also provides novel means for forming the ends of a toe binder for attachment to a shoe. As shown herein mechanism is provided for forming one end for attachment at one side of the shoe toe before the toe lasting is begun, and for thereafter forming the other end for attachment to the other side of the shoe toe. The formation of the binder may consist, as shown, in the bending of the binder into a loop or loops at each end of the binder.

A still further feature of the invention consists in means for inserting a fastening or fastenings in novel relation to a binder to assist in holding the binder in place. As herein shown one fastening is driven through a loop in the binder and another fastening is driven in such relation to the loop as to prevent straightening of the loop. Furthermore, as shown, the wire may be formed into a plurality of loops or bights, and securing means, for example tacks, may be driven through the respective loops.

Another feature of the invention consists in means for preparing an end of a binder for attachment to the shoe at a point remote

from the shoe and for then applying or presenting the end to the shoe in position for attachment thereto. The mechanism herein shown provides means for forming a loop 5 in each end of the binder wire successively while the wire is in a position remote from the shoe, means for feeding tacks to retaining mechanism above the loops while they are in such position, and means for then 10 advancing the wire and tacks to a position over the shoe to bring the tacks under drivers which drive the tacks to secure the loops to the shoe. In the lasting machine herein shown, the mechanism for effecting 15 this wire anchoring operation is then withdrawn out of the way while the lasting operation proceeds.

A further feature of the invention consists in means for applying a tension to the 20 binding wire after the completion of the toe lasting operation. To effect this, when the finishing side of the toe is reached in the lasting operation and the loop forming mechanism is operated to form a loop from 25 the strand of wire which extends around the toe, the tension on the toe wire is materially increased by the formation of the loop.

A further feature of the invention consists in means which is rendered operative 30 by the presence of the binding wire upon the shoe for causing the machine to sever the strand of wire beyond the finishing end of the binding wire. As herein shown, a cutting member is arranged to be moved 35 into operative position by the binding wire to cause a co-operating cutting device to become effective to sever the toe wire from the strand of wire leading from the supply of wire. As shown, one cutting device is 40 carried by the driver bar, and the normally inoperative co-operating member is carried by the means which advances the loop wire toward the shoe. When the wire advancing means is brought forward to secure the 45 wire to the finishing side of the shoe, the binding wire presses on the co-operating cutting member and moves it into operative relation to the cutting device carried by the driver bar, and the wire is severed 50 simultaneously with the driving of the tacks to secure the finishing end of the binding wire to the shoe and last. When the wire is attached to the shoe at the side where the lasting operation is begun there is, of 55 course, no binding wire in a position to cause the cutting device to operate and the wire is not severed.

Still another feature of the invention consists in a novel organization of means for 60 working the toe portion of an upper into lasted position over a shoe bottom, and means acting automatically to secure a binding wire to the toe, the construction shown comprising means for working different portions of the upper about the toe successively

into lasted position and for fastening the binder at the opposite sides of the toe successively.

These and other features of the invention will appear more fully from the following 70 detailed description when read in connection with the accompanying drawings and will be pointed out in the appended claims.

In the drawings.

Figure 1 is a front view of the head of a 75 hand method machine equipped with mechanism embodying my invention;

Fig. 2 is a plan view of mechanism embodying this invention;

Fig. 3 is a side view of parts of the mechanism shown in Fig. 2;

Fig. 4 is a detail of the clutch mechanism shown in Fig. 3;

Fig. 5 is a detail view, partly in section, of the wire feeding, bending, securing and 85 cutting mechanism;

Fig. 6 is a sectional plan view of the mechanism shown in Fig. 5;

Fig. 7 is a sectional detail of the wire cutting mechanism;

Fig. 8 is a perspective view of parts shown in Figs. 5 and 6;

Figs. 9, 10, 11 and 12 are details showing successive stages of the wire bending and 95 securing operations; and

Fig. 13 is a perspective view of the toe of a shoe after the binding wire has been applied thereto by this machine.

The mechanism embodying this invention is shown as applied to a hand method machine of usual construction, such, for example, as that shown in the patents referred to above and having the usual lasting mechanism comprising a gripper 2, tacking mechanism including a tack block and wiper 4, driver bar 6 having a driver 8 for inserting tacks one-by-one in a step-by-step operation of the machine when such work is required in side lasting; an edge rest 10; and a work rest 12. The rests 10 and 12 constitute 100 means for guiding and positioning the work for the binding wire securing operation, to be described, as well as for positioning and guiding the work for the operation of the lasting mechanism.

In Fig. 1 the driving pulley of the machine is represented by the numeral 14 on the shaft of which is a gear 16 connected to a gear 18 by an idler gear 20. The gear 18 is loose 115 on a shaft 22 which is journaled in a frame 23 secured to the main frame of the machine by bolts 25, and clutch mechanism, Figs. 2, 3 and 4, is provided for causing the shaft 22 to make one rotation in timed relation to the main shaft of the machine. The gear 18 has a projection 24 on its front face and a sleeve 26 pinned to the shaft 22 carries a pivoted member 28 which is impelled by a spring 30 to swing toward the gear 18 when 120 permitted to do so and engage the projec- 125

tion 24. The member 28 is normally held out of such engagement by interengaging wedge formations on the member 28 and on a rod 32 which may be pulled down by a connection 29 to a treadle (not shown) against a spring 34 to release the member 28 and set the clutch. When the rod 32 is allowed to rise as far as permitted by a pin 31, the wedge formation upon it comes into position to engage the corresponding formation on the member 28 and swings the member 28 away from the projection 24, whereupon rotation of the shaft 22 ceases.

Movement of the shaft 22 is limited to a single rotation for each depression of the treadle by the following mechanism. The rod 32 is in two parts 32, 33 which telescope together, and a spring 36 is provided which tends to separate the parts. A tension spring 34 is connected between the portion 33 of the rod and the frame. The spring 34 is, however, stronger than the spring 36 and therefore holds the parts of the rod telescoped and the spring 36 compressed. A latch 38 is mounted on the lower part 33 of the rod and is held in engagement with a notch 35 in the upper part 32 by a spring 40. When the lower part 33 of the rod is pulled down by the treadle connection 29 the latch 38 draws down the part 32 out of engagement with the member 28 allowing it to engage the lug 24 and cause rotation of the shaft 22. Continued downward movement of the latch 38 brings a cam shaped portion 44 of the latch into engagement with a stationary pin 46 which swings the latch away from the part 32 and permits the spring 36 to react and raise the part 32 into position to engage the member 28 and move it out of engagement with the lug 24 when a single revolution of the shaft 22 has been completed. The part 32 has a longitudinal slot which is engaged by the screw 48 (Fig. 4) to prevent rotation of the part and to permit its vertical movement.

Fixed on the forward end of the shaft 22 (Figs. 2 and 3) is a cam block 50 having cam paths by which the various parts of the binding wire handling and securing mechanisms are operated in a manner now to be described.

The tack driver bar 6 has an offset arm 52 carrying a pair of drivers 54. As shown in Fig. 2, a three-chambered tack pot is provided having chambers 58, 60 containing different kinds of tacks which are supplied respectively to raceways 61, 63 which deliver either one of the two kinds of tacks to the driver 54 for fastening respectively the heel seat and sides of the shoe, and having a chamber 62 containing mechanism for supplying tacks of the same kind to each of two raceways 63 of the binding wire securing mechanism. It is to be understood that during the toe fastening the last upper is preferably held in

place entirely by the toe binder, no tacks being separated from either of the raceways 61, 63. Means such as that disclosed in United States Letter Patent No. 1,981,672, granted December 16, 1934 on application of E. A. Stiggins, may be provided for preventing separation of tacks from either of the raceways 61, 63 during the toe fastening, the driver 54 then operating idle. These tacks are delivered to two tack chambers 10 73 (one of which appears in Fig. 6) in a block 72. In each chamber 10 is a tack retaining device comprising a block 74 having a curved tack engaging face and held in a tack retaining position by a spring 75. When the drivers 54 descend, the blocks 74 yield to allow the tacks to pass through the block and into the work. The binding wire is supplied from a reel 80 and passes therefrom through a friction device mounted on the rear end 85 of a stationary plate 82 which is fastened to the machine frame by a bracket 83. The friction device consists of an abutment 84 opposed to which is a plunger 86 backed by a spring 88 the tension of which may be adjusted by a screw 89. A wire passes between the abutment 84 and the plunger 86 and is held between these parts with sufficient friction to prevent backward movement of the wire end to apply suitable tension to the wire as it is drawn about the shoe toe. From the friction device the wire passes along a groove 89 in the lower face of the block 72, the groove 89 being covered by a cover plate 73 to form a wire guiding 100 passage. The block 72 (Fig. 2) is gibbed to the stationary plate 82 and is reciprocated toward and from the shoe by a link 92 pivoted at one end to the block 72 at 94 and at the other end to a lever 93. The opposite end of the lever 93 carries a cam roll engaging a cam path 28 in the cam block 50. To accommodate the link 92, the sliding block 72 is recessed on its lower side and the recess is closed at the bottom by a casing 101 in the lower face of which is formed a groove 102 which is a continuation of the groove 89 in the block 72. By the side of the groove 102 is mounted a dog 104 which is impelled by a spring 105 to grip the wire 110 when the slide 72 is moved forwardly and causes the wire to be fed forwardly with the forward movement of the block 72, the friction plunger 86 preventing backward movement of the wire when the block 72 is retracted.

Beneath the forward end of the stationary plate 82 is a casing 101 supported by the frame 23 and in the casing is mounted for rotation a spindle 106 (Figs. 1 and 5) constituting a part of the wire manipulating mechanism by which a bight or loop is formed in the wire. The spindle 106 carries two pins 107 which at times extend above the plate 82 into a recess in the slide 72 one 120 125 130 135 140 145 150 155 160 165 170 175 180

on each side of the path of the wire. By forward movement of the slide 72 the end portion of the binding wire is fed between the pins 107. Splined on the spindle 106 is a pinion 108 which is actuated at times to rotate the spindle 106 by means of a lever 110 pivoted at 112 and having one end formed as a toothed segment 114 engaging the pinion 108 and the other end carrying a cam roll which engages a cam path 116 in the cam block 50. When the spindle 106 is rotated by the cam 116 the pins 107 act upon the wire lying between them to form it into loops or lights, as shown in Fig. 10. To free the pins 107 from the bent wire the spindle 106 is moved vertically through the pinion 108 by an angle lever (Fig. 1) pivoted at 118 and having one arm 120 connected at 121 to the spindle 106 and the other arm 122 carrying a cam roll arranged to engage an edge cam 124 on the cam block 50. A spring 127 actuates the lever 120, 122 in one direction and holds the cam roll 122 in the other direction. The arm 122 is connected by a link 126 to a tack separating slide 130 of usual construction in machines of this type which reciprocates across the ends of the raceways 66 and separates one tack at a time from each raceway.

Mechanism is provided for severing the portion of wire used to bind the toe from the strand of wire leading to the reel and the mechanism preferably acts simultaneously with the securing of the finishing end of the binding wire to the shoe. During the toe lasting operation the toe binding wire is drawn through the block 72 of the loop forming mechanism and to the right across a projecting end 132 (Fig. 7) of a lever 134 pivoted to the block 72 at 136 and having a pin on its opposite end engaged by a spring 138 which normally holds this end of the lever 134 out from under the strand of wire (Fig. 6). When the block 72 advances toward the shoe, however, to carry the wire into position to be secured to the shoe on the finishing side of the toe, the binding wire will bear on the end 132 of the lever 134 and cause the opposite end to swing beneath the wire and into position to co-operate with a cutter 140 which is mounted with the drivers 54 on the driver bar offset arm 52 and when the drivers descend passes close to and below the upper surface of the lever 134 and shears off the wire. When the block 72 is withdrawn after the binding wire is secured, the dog 104 permits the wire to remain stationary, being held by the friction plug 86, while the block 72 moves rearwardly and the wire is thus fed by relative movement of the block 72 and the plug 86 to the bending device 106, 107 for the next operation.

The mechanism has now been sufficiently

described to enable the operation of the machine to be followed. Before the lasting of the toe of a shoe on the hand method machine is begun, it is necessary to fasten the binding wire at the side of the toe where the lasting is to begin, for example, at the point *a*, Fig. 13. For this operation the shoe is presented to the machine against the edge rest 10 and bottom rest 12 with the toe pointing toward the left (Fig. 2). The treadle is depressed and moves the rod 32 downwardly to set the shaft 22 in motion. The end portion of the wire is in the position shown in Fig. 9 and as the pinion 108 and spindle 106 are caused to rotate by the mechanism described, the pins 107 engage the wire and bend it, as shown in Figs. 6 and 10. The spindle 106 is then depressed to bring the pins 107 below the looped wire, as shown in Fig. 11, and the separator 130 is simultaneously operated and drops two tacks, one into each of the two tack pockets 70 in the slide 72. The slide 72 is then brought forward toward the shoe to position the two tacks and the loops in the wire beneath the drivers 54 (Fig. 11) whereupon the tacks are driven through the loops into the shoe, as shown in Fig. 12, to securely hold the leading end of the binding wire in position. This initial attachment of the binding wire is also shown in Fig. 6, the slide 72 being immediately withdrawn, as shown in Fig. 2. The binding wire having been secured, the operator proceeds with the operation of lasting the toe upon the machine in the usual manner. After this operation is completed, the shoe is in position with the toe pointing toward the right and with the finishing side of the lasted toe adjacent to the wire manipulating and securing mechanisms. The treadle is now again depressed and the pins 107 again operated to form loops in that intermediate portion of the wire strand which is to form the end portion of the binding wire of the lasted toe. These loops are partly formed from the portion of wire which extends around the toe of the shoe and hence additional tension is applied to the binding wire by the formation of the loops which results in setting the binding wire hard against the upper and forming the upper closely into the angle between the feather and lip of the innersole. The loop thus formed is advanced to the shoe and secured, as shown at *b* in Fig. 13, similarly to the advancing and securing of the beginning end of the wire. Simultaneously with the securing of the finishing end of the toe binding wire to the shoe, the strand of wire leading to the supplying reel is severed. This binding wire at the time the finishing end is secured bears against one end of the lever 134 (Fig. 7) and swings its other end into position to co-operate with the cutting member 140 so that 130

when the member 140 descends with the drivers 54 to secure the loop, the wire is severed beyond the point secured, leaving the shoe free to be withdrawn from the 5 chine.

Having fully described my invention what I claim as new and desire to secure by United States Letters Patent is:

1. In a binder applying mechanism, the 10 combination with means for inserting fastenings, of means to guide a binder in position to bind a shoe upper progressively from one side of the shoe around to the other side, and means to manipulate the binder into a form to cause it to be secured by the fastening to the shoe.

2. In a binder applying mechanism, the 15 combination with means for inserting fastenings, of means to guide a binder in position to bind an upper progressively from one side of the shoe around to the other side, and means so to form an end portion of the binder as to cause it to be anchored effectively by said fastenings against endwise movement.

3. In a binder applying mechanism, the 20 combination with means for inserting fastenings, of means to guide a binder in position to bind an upper progressively, means acting so to form an end portion of the binder as to prepare it to be anchored effectively by a subsequently inserted fastening and means for then operating the inserting means to anchor the binder.

4. In a binder applying mechanism, means to insert fastenings, means to produce in binding material a formation adapted to co-operate with a fastening in anchoring the binder and means for subsequently operating the inserting means to anchor the binder.

5. In a binder applying mechanism, means to drive fastenings, means to produce in binding material a formation independently of the fastenings, a formation adapted to co-operate with a fastening in anchoring the binder and to cause said formed portion and a fastening in binder anchoring relation to the shoe, and means for operating the fastening driving means in timed relation to the binder forming means.

6. In a binder applying mechanism, means to drive fastenings, and means to produce in binding material a formation adapted to co-operate with a fastening in anchoring the binder, and means to apply tension to the strand of binding material while the shoe and said material are moved relatively to effect the toe binding operation, said machine being further constructed and arranged to effect a formation in the strand of binding material adapted to connect with a second fastening to anchor the binder when the toe is bound.

7. In a binder applying mechanism, the

combination with means for inserting fastenings, of means to bend a binder end independently of the fastenings to adapt it to be anchored by a fastening.

8. In a binder applying mechanism, the 70 combination with means for inserting fastenings, of means adapted for operation at the will of the operator to produce a bend in a strand of toe binding wire to adapt it to be anchored by a fastening at the beginning of a fastening operation around the toe of the shoe.

9. In a machine of the class described, the 75 combination with gripper lasting means and means to guide a binder in position to bind an upper progressively around the toe from one side of a shoe to the other side, of means to anchor the binder in toe binding relation at the end of the operation of binding the toe.

10. In a machine of the class described, the combination with means for inserting fastenings and a gripper for lasting successive portions of an upper, of means to guide a binder in position to bind an upper in basted position as it is progressively lasted from one side of the toe around the toe to the other side, and means arranged for operation at the will of the operator to anchor the binder in toe binding relation at the 95 end of the operation of lasting the toe.

11. In a binder applying mechanism, the combination of means to guide a binder in position to bind an upper progressively around the toe of a shoe, and means arranged for operation at the will of the operator to effect anchorage of the binder after the toe has been bound and to sever the anchored binder from the strand of binding material.

12. In a binder applying mechanism, the combination with means for inserting fastenings, of means to manipulate the end of a binder to produce a double loop and present it in position for the binder end to be anchored by fastenings driven by the inserting means.

13. In a binder applying mechanism, binder supplying means, means for automatically forming independently of the shoe a bight in one end portion of the binder, and means for driving a fastener in relation to the bight to anchor the binder.

14. In a binder applying mechanism, means for automatically forming a bight in a wire, and means for driving two tacks, one through the bight in the wire and one at one side of the bight to prevent the bight from straightening.

15. In a binder applying mechanism, means for automatically forming a plurality of bights in the wire, and means for driving a tack in each of the bights so formed.

16. In a binder applying mechanism,

means arranged to be set in operation at the will of the operator at the side of a shoe toe where the lasting is begun and at the side of the shoe toe where the lasting is finished to form a bight in binder wire and advance the bight to the shoe, and means for inserting a fastening to hold the bight and wire to the shoe.

17. In a binder applying mechanism, means arranged to be set in operation at the will of the operator at the side of a shoe toe where the lasting is begun and at the side of the shoe toe where the lasting is finished to form a bight in binder wire, advance the bight to the shoe and insert a fastening to hold the bight and wire to the shoe, and means rendered operative by the presence of the binding wire about the shoe to sever the wire from the strand of supply.

18. In a toe binding machine, the combination with operating means, of binding wire securing mechanism constructed and arranged to be set in operation by the operator to manipulate in turn each end of a toe binding wire to form a loop and to secure the respective loops of the toe binder successively to a shoe toe to hold the upper in lasted position.

19. In a toe binding machine, means for supplying a continuous strand of wire to a shoe toe which is being lasted, automatic means for securing the wire to the shoe constructed and arranged to be set in operation by the operator at the beginning and at the end of the lasting operation to secure first one end of the binding wire and then the other end to the shoe to hold the upper in lasted position, and means for severing the wire beyond the point thus secured.

20. In a toe binding machine, means for automatically forming a loop at the end of a continuous strand of wire and inserting through the loop a tack to secure the wire to a shoe, and means under the control of the operator to cause said means to secure another portion of the wire to the shoe at another point.

21. In a toe wiring machine, means for forming in a wire a loop and inserting through the loop a tack to secure the wire to a shoe, said means being under the control of the operator to secure the binding wire in position at the beginning and at the end of the toe wiring operation, and means constructed and arranged to be effective only at the end of the toe wiring operation for severing the binding wire.

22. In a toe wiring machine, means for forming a loop in a continuous strand of wire and inserting through the loop a tack to secure the wire to a shoe at the end of the toe wiring operation, and means constructed and arranged to be rendered effective by the presence of the binding wire

about a toe for severing the continuous strand from the binding wire beyond the end of the binding wire.

23. In a toe wiring machine, means for forming a loop in a continuous strand of wire and inserting through the loop a tack to secure the wire to a shoe at the end of the toe wiring operation, and means constructed and arranged to be rendered effective by the presence of the wire on one side of the point secured for severing the wire on the other side of the point secured.

24. In a toe binding mechanism, means for securing a continuous strand of wire to a shoe at the end of the toe wiring operation, and means constructed and arranged to be rendered effective by the presence of the binding wire about the shoe toe for severing the continuous strand from the binding wire beyond the point where the binding wire is secured to the shoe.

25. In a toe binding machine, means for forming a bend in a wire supplied in a continuous strand, means comprising a driver bar for inserting a tack in the bend of the wire at the end of the toe wiring operation, wire cutting means carried by the driver bar, and co-operating cutting means moved into operative relation to the cutting means by pressure of the binding wire and causing the cutting means to sever the strand of wire beyond the point where it is secured at the end of the toe wiring operation.

26. In a toe binding machine, binding wire manipulating mechanism comprising a pair of pins, means for feeding the wire between the pins, means for rotating the pins to bend the wire, means for retracting the pins, means for advancing the bent wire to the work, and means for inserting a tack through the bend of the wire to secure it to the work.

27. In a toe binding machine, a pair of pins, means for advancing a continuous strand of wire between the pins, means for rotating the pins to form two bights in the wire, means for moving the wire and pins relatively to free the bights from the pins, means for advancing the wire toward a shoe, and means for inserting tacks through each of the bights to secure the wire to the shoe.

28. In a machine of the class described, the combination of means for forming a loop in the end of a strand of wire, and means for thereafter inserting a fastening to secure the loop.

29. In a machine of the class described, the combination of means for forming a loop in the end of a binding wire, means for advancing the loop to the shoe, and means for securing the loop to the shoe so that during the toe lasting operation the wire may be drawn around the toe as the toe is lasted, the loop forming and securing means being operable a second time after the toe lasting is

- completed to form a second loop and secure it to the shoe on the opposite side of the toe from the first loop.
30. In a machine of the class described, the combination of means for automatically bending a continuous strand of wire into a loop, and means for inserting a fastening through the loop to secure the strand. 76
31. In a machine of the class described, the combination of means for automatically forming a loop in a continuous strand of wire, and means for inserting automatically a fastening to secure the loop to a shoe. 75
32. In a machine of the class described, the combination of means for forming a loop in the wire, means for inserting a tack through the loop, and means for inserting another tack at one side of the loop to prevent straightening of the loop. 80
- 20 33. In a machine of the class described, the combination of means for bending the wire into a loop, means for inserting a fastening in the loop to hold the loop to a shoe, and means for inserting another fastening 85
- 25 in the shoe in such a position as to prevent reverse bending of the loop when the wire is placed under strain. 90
34. In a machine of the class described, means for forming loops successively in a binding wire supplied in a continuous strand, and means for securing one of said loops on either side of the shoe toe, said loop forming mechanism being so constructed and arranged that, after a loop is formed 95
- 35 and secured to one side of the toe, the loop for the second attachment at the other side of the toe will be formed from the binding wire which extends around the toe and will tighten that portion of the wire to hold the upper in lasted position. 100
- 40 35. In a toe binding machine, means for securing a binding wire to a shoe on the side where the lasting operation of the toe is to begin, means for tensioning the wire to hold the upper in lasted position while the shoe is being lasted, and means operable at the will of the operator for securing the binding wire to the shoe at the side of the shoe where the toe lasting operation is finished. 105
- 45 36. In a toe binding machine, means for securing one end of a binding wire to a shoe, means for progressively drawing the wire about the toe from one side to the other side 110
- 50 to hold the upper in lasted position, and means for securing the other end of the binding wire to the shoe. 115
37. In a toe binding machine, means for positioning and guiding a shoe, and means operable at will while the shoe is held against said positioning and guiding means to secure to the shoe the ends of a binding wire extending about the lasted toe. 120
- 60 38. In a toe binding machine, means for positioning and guiding a shoe, and means 125
- 65 operating automatically to advance the end of the binding wire to the shoe and to secure it thereto while the shoe is held against the positioning and guiding means before the toe is lasted and operable again after the toe lasting operation while the shoe is still held against the positioning and guiding means to advance and secure to the shoe the opposite end of the binding wire to hold the upper in lasted position. 130
39. In a toe binding machine, means for positioning and guiding the shoe during the toe lasting operation, and means operable at will while the shoe is held against said positioning and guiding means first to secure one end of the binding wire to a shoe and fast at the side of the toe at which the lasting operation is begun and then to secure the wire at the side of the shoe toe at which the lasting operation is completed. 135
40. In a toe binding machine, means for positioning and guiding a shoe, and means operating automatically to advance the end of the binding wire to the shoe and to secure it thereto while the shoe is held against the positioning and guiding means at the beginning of the binding operation and operable again at the end of the operation while the shoe is still held against the positioning and guiding means to advance and secure to the shoe the opposite end of the binding wire to hold the upper in lasted position, said means acting to tension the wire about the toe before it is finally secured. 140
41. In a machine of the class described, the combination of guiding and positioning means for the shoe, means for twisting a strand of binding wire into a loop, means for advancing the loop to a position over the shoe, and means for securing the loop to the shoe toe at one side of the toe, said means acting when they are again operated at the other side of the shoe toe to form a loop from the portion of wire extending about the toe whereby the toe binding wire is tensioned and a second loop is formed and secured to the shoe toe. 145
42. In a machine of the class described, means for positioning a shoe, and power operated means for advancing and securing the end of a continuous strand of wire against endwise movement to the shoe while held against said positioning means, the wire being drawn about the shoe toe and the wire securing means being again operated after the toe has been encircled by wire to advance and secure the wire to the toe on the opposite side of the shoe from the side where it was first secured. 150
43. In a binder applying mechanism, the combination of means to guide a strand of binding material in position to bind an upper progressively around the toe of a shoe, and means arranged to sever a section of said material and to anchor the severed end 155

of the material to the shoe after the strand has been positioned round the toe.

44. In a toe binding machine, the combination with operating means, of binding wire securing mechanism constructed and arranged to manipulate in turn each end of a toe binding wire to form a loop and to secure the respective ends of the toe binder by said loops successively to a shoe toe to hold the upper in lasted position.

45. In a toe binding machine, means for supplying a continuous strand of binding material to the toe of a lasted shoe, power operated means for securing first the end of the binding material to the shoe at one side of the shoe and then securing an intermediate portion of the binding material to the shoe at the opposite side of the shoe, and means for severing the binding material beyond the point last secured.

46. In a machine of the class described, means for pulling upon a binder extending about the forward portion of a shoe with one end secured thereto and bending it to form a loop, and means for driving a tack in the loop to maintain the binder under tension.

47. In a machine of the class described, means for pulling upon a binder having an end attached to a shoe and extending about the forward portion of the shoe and forming therein a loop, and automatically operating means for then fastening the loop to the shoe.

48. In a machine of the class described, mechanism constructed and arranged to be set in operation by the operator and acting automatically to tighten a binder about a shoe, operate upon the binder to condition it for attachment to the shoe, and then to drive a fastening to secure the binder after the operation on the binder has been completed.

49. In a machine of the class described, the combination with tack driving means, of binder bending means comprising a rotatable bending device having means thereon to engage and bend the binder, means for turning the device to bend the binder, and means for then actuating the driving means to insert a tack in the bend of the binder.

50. In a machine of the class described, means for pulling upon a binder attached to a shoe and extending about the forward portion of the shoe and bending the binder, and means for then fastening the binder.

51. In a machine of the class described, mechanism independent of the shoe for bending a binder, means for carrying the binder over the shoe bottom and presenting the binder in predetermined relation to tack driving means, and tack driving means operating automatically to secure the bent binder to the shoe.

52. In a machine of the class described,

binder fastening mechanism comprising a tack driver, a tack block movable over a shoe bottom, means for bending a binder in the tack block, means for moving the tack block and bent binder over the shoe bottom, and means for operating the driver to drive a tack in the bend of the binder.

53. In a machine of the class described, tack drivers, means movable relatively to the tack drivers for presenting a binder in predetermined relation to the tack drivers, and means for operating the drivers to secure the binder to the shoe.

54. In a machine for binding the toes of shoes, the combination of a tack driver, a wire bender, and means for operating the bender prior to the operation of the tack driver.

55. In a machine of the class described, the combination with means for manipulating a toe binder so that it may be secured by a fastening, without further manipulation of means for driving a fastening to secure the binder after it has been so fully manipulated.

56. In a machine of the class described, the combination with means for cutting a binder from a strand of continuous material, of means for manipulating the binder to enable it to be secured by a tack, and means for thereafter driving a tack to secure the binder.

57. In a machine of the class described, the combination with shoe positioning means, of binder forming means constructed to bend portions of the binder for attachment to the shoe, and means for securing the portions thus formed to the shoe.

58. In a machine of the class described, the combination with shoe positioning means, of means for preparing the end portions of a binder with loop formations for attachment to the shoe, and means for applying the binder to the shoe and inserting fastenings through the previously prepared loop formations.

59. In a machine of the class described, the combination with means for working an upper over the bottom of a last, of means for positioning a binder in relation to the shoe, and power operated means for fastening the end portion only of the binder by anchor tacks first at one side of the shoe and then at the other side of the shoe.

60. In a machine of the class described, the combination with means for working an upper over a last, of means for driving an anchor tack at one side of the shoe to fasten a binder, and means for tensioning the binder about the toe and for fastening it to an anchor tack at the opposite side of the shoe.

61. In a machine of the class described, the combination with means for working an upper into lasted position round the end of a last, of means operating in conjunction

with said first named means to tension a binder round the end of the shoe and to fasten it at opposite sides of the shoe successively.

5 62. In a machine for binding the toes of shoes, the combination of means for forming the ends of a binder to adapt them for attachment to a shoe, and means for presenting the formed ends to the shoe and for fastening them to the shoe. 70

10 63. In a machine for binding the toes of shoes, the combination of means for forming a loop in the end of a binder, and means for advancing the looped end of the binder 15 and locating it in position for attachment to the shoe. 80

15 64. In a machine for binding the toes of shoes, the combination of means for forming the respective ends of the binder for attachment to the shoe, and means for presenting binder ends successively in position for attachment to the shoe. 85

20 65. In a toe binding machine, the combination of means for advancing a toe binder one end at a time from a remote position into position for attachment to a shoe toe, and fastening inserting means operating in time relation to said advancing means to secure the binder to the shoe. 90

25 66. In a machine for binding the toes of shoes, the combination of means for forming the end of a binder to adapt it for attachment to the shoe, and means for presenting the formed end in position for attachment 30 to the shoe. 95

30 67. In a machine for binding the toes of shoes, the combination of means for operating on a shoe upper, and means for forming an end of a binder for attachment to the 35 shoe before it is attached to the shoe. 100

40 68. In a machine for binding the toes of shoes, the combination of means for working an upper over the end of a last, means for forming the ends of a binder one at a 45 time for attachment to the shoe, and means for presenting the binder ends in position for attachment to the shoe. 105

45 69. In a toe binding machine, the combination of means for working an upper over the end of a last, means independent of the overworking means for forming the ends of a toe binder for attachment to a shoe, for 50 presenting the binder ends to the shoe, and fastening means operating to secure the binder to the shoe. 110

55 70. In a toe binding machine, the combination of means for working an upper over the end of a last, and means for forming the ends of a toe binder for attachment to a shoe, 55 and fastening them to the shoe toe successively. 115

60 71. In a toe binding machine, the combination of means for working an upper over the end of a last, means for forming the ends of a toe binder for attachment to a shoe, 60 and fastening them to the shoe toe successively. 120

65 72. In a machine of the class described, the combination with means for holding a binder under tension while being applied to a shoe toe to hold the upper in lasted position, of mechanism for preparing the end of the binder for attachment to the shoe, 70 fastening inserting means, a support for the binder end, and means for relatively moving the binder support and the fastening inserting means to effect presentation of the binder end in operative relation to the 75 fastening inserting means. 80

73. In a machine of the class described the combination with end lasting mechanism, binder supplying means, and means to apply tension to the binder, of mechanism arranged to receive the binder end in a position remote from the shoe and movable to carry the binder end to the shoe being lasted. 85

74. In a machine of the class described, the combination with end lasting mechanism, 90 having means for applying tension to binder material round the end of a shoe, and means for imparting operating movement to the lasting mechanism, of mechanism operative in time relation to the lasting mechanism, 95 to carry a severed end of the binding material to the lasted shoe.

75. In a machine of the class described, the combination with means for working an upper over a last, of fastening means arranged to engage a shoe binder successively on opposite sides of the shoe, and power operated connections for imparting to said fastening means operative movements to fasten the binder to the shoe first at one 100 side of the shoe and then at the other. 105

76. In a machine of the class described, the combination with means for working an upper into lasted position round the end of a last, of means for driving anchor tacks 110 successively at opposite sides of the shoe and for bending the ends of a lasting binder first at one side of the shoe and then at the other side to enable it to be secured by said tacks. 115

77. In a machine of the class described, the combination with means for working an upper over a last, of tacker mechanism, power operated connections to said mechanism for operating it to drive anchor tacks first at one side of the shoe and then at the other, and means for presenting a binder in position to be secured by the anchor tacks. 120

78. In a machine of the class described, the combination with means for working an upper over a last, of means for positioning a binder for attachment to the end of a shoe and for fastening it to anchor tacks at the sides of the shoe successively. 125

79. In a machine of the class described, 130

the combination with means for working an upper over a last, of tacker mechanism, power operated connections to said mechanism for operating it to drive anchor tacks

- 5 first at one side of the shoe and then at the other, binder bending mechanism, and power operated connections to said bending mechanism for operating it in time relation to the tacker mechanism to fasten a binder to the

10 shoe with its ends bent around said tacks.

80. In a machine of the class described, the combination with shoe positioning means and a supply of binder material, of a tacker and binder bending device mounted for

- 15 movement toward a shoe positioned by said positioning means, a cutter carried by said device, and power driven connections for operating said cutter to sever a portion of the binder material and for operating said

20 tacker and bending device first to bend the binder and then to drive a tack to secure the bent binder.

81. In a machine of the class described, the combination with shoe positioning means, of a device mounted for movement to apply binding material to a shoe, a cutter, power means for operating the cutter to sever a portion of said material, and additional power operated means for fastening the binder to the shoe.

82. In a machine of the class described, means for progressively lasting successive portions of a shoe upper over the bottom of a last, and power operated means for securing the end of a binder to the shoe prior to the progressive lasting operation, the binder being carried round the shoe toe from side to side in holding engagement with the upper as the lasting progresses, said power operated means being operative after the lasting is finished to secure the other end of the binder to the shoe.

83. In a machine of the class described, means for progressively lasting successive portions of a shoe upper, binder supplying means, and means acting automatically when set in motion by the operator to present and fasten the binder to the shoe at the beginning and end of the lasting operation.

84. In a machine of the class described, the combination with a wiper for progressively lasting an upper about the end of a shoe, of power operated means for fastening a binder to the shoe prior to the commencement of the lasting operation to cause the binder to be drawn under the wiper as the lasting progresses, and means for fastening the binder to the shoe after the lasting operation is concluded.

85. In a machine of the class described, the combination of means for progressively lasting a shoe upper and progressively and simultaneously carrying a binder round the

toe of the shoe from one side to the other, 65 and means operative in conjunction with said lasting means for fastening the binder at opposite sides of the shoe successively.

86. In a machine of the class described, the combination with lasting grippers 70 operating progressively to updraw, overdraw and plait a shoe upper about the toe of the shoe, of means arranged to be set in operation at the will of the operator automatically to advance and secure a binding 75 wire to the shoe toe at the beginning and at the end of the toe lasting operation.

87. In a machine of the class described, means acting automatically to secure a binding wire to a shoe arranged to be set in 80 operation at the will of the operator successively at different points about the periphery of the shoe, and means for progressively lasting the upper between the points where the binding wire is secured.

88. In a machine of the class described, means acting automatically to secure either the end or an intermediate portion of a continuous binding wire to a shoe arranged to be set in operation at the will of the operator 90 to secure the wire to the shoe at successive points about the periphery of the shoe, and means for progressively lasting the shoe upper located between said points.

89. In a machine of the class described, 95 the combination of means for supplying a continuous strand of binding material under tension, power means for securing the end of the binding material to the shoe at one side of the shoe toe, and a power operated gripper for progressively lasting the upper about the shoe toe while carrying the binder under tension about the shoe toe, said power means being again operable after the toe is lasted and bound to secure the binding material to 100 the shoe at the opposite side of the shoe toe.

90. In a machine of the class described, the combination of lasting grippers operated by power progressively to updraw, overdraw and plait successive portions of a shoe 110 upper about the toe of a shoe, and means arranged to be set in operation at the will of the operator automatically to secure a binding wire to the shoe toe at the beginning and again at the end of the toe lasting 115 operation.

91. In a machine of the class described, a gripper having updraw, overdraw and plaiting movements for progressively lasting successive portions of a shoe upper located 120 between separated points about the periphery of a shoe, and means arranged to be set in operation at the will of the operator and acting automatically to secure the end of a continuous binding wire to the shoe where the lasting is begun and to secure an intermediate portion of the wire to the shoe 125 where the lasting operation is ended.

92. In a machine of the class described, means for progressively lasting successive portions of a shoe upper, and mechanism for securing a binder to hold an upper in 5 overworked position about the forward portion of a shoe comprising fastening inserting means, means associated with the fastening inserting means for presenting the binder in predetermined relation to the fastening inserting means, and means for operating the said inserting means to secure the binder to the shoe. 10 lasted to secure the binding material to the shoe at the opposite side of the shoe toe. 65
93. In a machine of the class described, the combination of means for progressively 15 lasting successive portions of an upper, a tuck driver, wire supplying means, a wire bender, and means for operating the bender and driver to secure the wire to a shoe. 70
94. In a machine of the class described, 20 the combination of means for progressively lasting successive portions of a shoe upper, means for manipulating a toe binder to be secured by a fastening, and means for driving a fastening to secure the binder to the shoe. 75
95. In a machine of the class described, the combination of means for cutting a binder from a strand of continuous material, means for progressively lasting successive 30 portions of a shoe upper, means for manipulating the binder to enable it to be secured by a fastening, and means for driving a fastening to secure the binder. 80
96. In a machine of the class described, 35 the combination of means for progressively lasting successive portions of a shoe upper at the toe, means for carrying a toe binder over the shoe bottom and presenting the binder in predetermined relation to the fastening means, and fastening means operating automatically to secure the binder to the shoe. 85
97. In a machine of the class described, 40 the combination with shoe positioning means and lasting means, of binder supplying means, means for driving a tack, and additional means for causing the end of the binder to be secured to a shoe by said tack, said lasting means being operative upon movement of the shoe guided by said positioning means to last the upper and cause the binder to be drawn against it, said tacking means and additional means being operative to fasten the other end of the binder 50 to the shoe after the upper has been lasted. 90
98. In a machine of the class described, 45 the combination of means for supplying a continuous strand of binding material, power means for securing the end of the binding material to the shoe at one side of the toe, and means for progressively lasting the upper about the shoe toe while carrying the binder about the shoe toe, said power means being again operable after the toe is 60
99. In a machine of the class described, the combination with a lasting gripper operating progressively to updraw, overdraw and plait a shoe upper about the toe of a shoe, of means arranged to be set in operation at the will of the operator to secure a binding wire to the shoe toe at the beginning and at the end of the toe lasting operation. 75
100. In a machine of the class described, means acting automatically to form and secure a binding wire to a shoe arranged to be set in operation at the will of the operator, and means for progressively lasting the upper between the points where the binding wire is secured. 80
101. In a machine of the class described, the combination of means for supplying a continuous strand of binding material, power means for securing the end of the binding material to the shoe at one side of the shoe toe, a gripper, and means for causing the gripper to updraw and overdraw successive portions of the upper progressively about 90 the toe while the binder is carried about the shoe toe, said power means being again operable after the toe is lasted to secure the binding material to the shoe at the opposite side of the shoe toe. 95
102. In a machine of the class described, the combination of power operated mechanism for attaching the end of a binder to one side of a shoe, and means for lasting the upper as the shoe is rotated relatively 100 to said mechanism, said mechanism being again operable after the shoe has been rotated to fasten the binder to the shoe on its opposite side. 105
103. In a machine of the class described, means for progressively lasting successive portions of a shoe upper, means for pulling upon a binder extending about the forward portion of a shoe to hold the upper in lasted position, and means for fastening the binder 110 to the shoe. 110
104. In a machine of the class described, means for progressively lasting successive portions of a shoe upper, means for pulling upon a binder extending about the forward portion of a shoe and bending it to form a loop, and means for driving a tack in the loop to maintain the binder under tension. 115
105. In a machine of the class described, means for progressively lasting successive portions of a shoe upper, means for pulling upon a binder extending about the forward portion of a shoe and forming therein a loop, and automatically operating means for then fastening the loop to the shoe. 120
106. In a machine of the class described, means for progressively lasting successive portions of a shoe upper, and mechanism 125

constructed and arranged to be set in operation by the operator after the lasting operation and acting automatically to tighten a binder about a shoe, manipulate the binder 5 to condition it for attachment to the shoe, and then drive a fastening to secure the binder.

107. In a machine of the class described, the combination with fastening driving 10 means and means for progressively lasting successive portions of a shoe upper, of binder bending means comprising a rotatable binder bending device having means thereon to engage and bend the binder, means for turning 15 the device to bend the binder, and means for then actuating the driving means to insert a fastening in holding relation to the bend of the binder.

108. In a machine of the class described, 20 the combination of means for progressively lasting successive portions of a shoe upper in position to be held by a binder, mechanism for securing the binder to hold an upper in overworked position about the for-

ward portion of a shoe, comprising a tack 25 driver, a tack block movable over a shoe bottom, means for bending the binder in the tack block, means for moving the tack block and bent binder over the shoe bottom, and means for operating the driver to drive a 30 tack in the bend of the binder.

109. In a machine of the class described, a gripper having updraw, overdraw and plaiting movements for progressively lasting 35 successive portions of a shoe upper located between separated points about the periphery of a shoe, means arranged to be set in operation at the will of the operator and acting automatically to secure the end of a continuous binding wire to the shoe where 40 the lasting is begun and to secure an intermediate portion of the wire to the shoe where the lasting operation is ended, and means acting to sever the wire near the point 45 where it is last secured to the shoe.

In testimony whereof I have signed my name to this specification.

BERNARD T. LEVEQUE.
